DESIGN FOR A CANDY CONFECTION

Gardner E. Wheeler, New Haven, Conn., assignor
to The Bradley Smith Company, New Haven,
Conn., a corporation of Connecticut

Application May 14, 1935, Serial No. 56,835

Term of patent 7 years

To all whom it may concern:

Be it known that I, Gardner E. Wheeler, a citizen of the United States, residing in New Haven, in the county of New Haven and State of Connecticut, have invented a new, original, and ornamental Design for a Candy Confection, of which the following is a specification when taken in connection with the accompanying drawing:

Fig. 1 is a side elevational view of a candy confection showing my new design;

Fig. 2 is a side elevational view taken at right angles to the view shown in Fig. 1; and

Fig. 3 is a top plan view of the candy confection.

The piece of candy embodying my design is shown as attached to the usual stick or handle by which it may be held.

I claim:

The ornamental design for a candy confection substantially as shown.

GARDNER E. WHEELER.
